[57] CLAIM

The ornamental design for a forend support for hand gun, as shown and described.

DESCRIPTION

FIG. 1 is a side elevational view of a forend support for hand gun according to my design; a hand gun phantomed in dashed lines thereon forms no part of my design;

FIG. 2 is an enlarged side elevational view of my forend support for hand gun, the other side view being a mirror image of FIG. 2;

FIG. 3 is a front elevational view thereof;

FIG. 4 is a rear elevational view thereof;

FIG. 5 is a top plan view thereof; and

FIG. 6 is a bottom plan view thereof.

FIG. 1

FIG. 2

FIG. 3

FIG. 5

FIG. 6

FIG. 4
